(57) **CLAIM**

The ornamental design for a combination scraper and scoop, as shown and described.

DESCRIPTION

FIG. 1 is a front, top perspective view of a combination scraper and scoop showing my new design.

FIG. 2 is a front elevation view thereof.

FIG. 3 is a rear elevation view thereof.

FIG. 4 is a right side elevation view thereof.

FIG. 5 is a left side elevational view thereof.

FIG. 6 is a top plan view thereof; and,

FIG. 7 is a bottom plan view thereof.

The broken lines shown in the drawings represent portions of the combination scraper and scoop that form no part of the claimed design.
